UNITED STATES PATENT OFFICE.

ISAAC WAGEMAKER, OF ATHENS, TENNESSEE, AND ELMER G. BRETZIN, OF ENSLEY,
AND VERNE C. FOSTER, OF BIRMINGHAM, ALABAMA.

DESIGN FOR A RUBBER HEEL.

Application filed September 12, 1922. Serial No. 3,707. Term of patent 7 years.

To all whom it may concern:

Be it known that we, ISAAC WAGEMAKER, residing at Athens, in the county of McMinn and State of Tennessee, and ELMER G. BRETZIN and VERNE C. FOSTER, residing at Ensley and Birmingham, in the county of Jefferson and State of Alabama, citizens of the United States, have invented a new, original, and ornamental Design for a Rubber Heel, of which the following is a specification, reference being had to the accompanying drawing, forming a part thereof.

Figure 1 is a perspective view of a rubber heel, showing our new design.

Figure 2 is a transverse section showing our new design.

What we claim is:

The ornamental design for a rubber heel, as shown.

ISAAC WAGEMAKER.
E. G. BRETZIN.
V. C. FOSTER.
